D12-204. OR D 12,423 EX

Design No. 12,423, dated August 16, 1881.

UNITED STATES PATENT OFFICE.

WILLIAM HAILES, OF ALBANY, NEW YORK.

DESIGN FOR A CAR-WHEEL.

SPECIFICATION forming part of Design No. 12,423, dated August 16, 1881.

Application filed July 16, 1881. Term of patent 7 years.

To all whom it may concern:

Be it known that I, WILLIAM HAILES, of the city and county of Albany, and State of New York, have originated and invented a new 5 Design for the Plate or Web of Car-Wheels, the following being a full, clear, and exact description, reference being had to the accompanying photographic illustrations, making part of this specification.

10 The annexed photographic illustrations (marked Figure 1 and Fig. 2) are reduced views taken, respectively, from the front and back of a car-wheel, in which similar letters of reference indicate corresponding parts in the 15 two figures.

The nature of my design relates to the configuration of the plate or web of a single-plated car-wheel (that part of the wheel which connects the hub and rim together) by arranging 20 in one design certain known forms heretofore existing separately, and as a result of their union producing new forms and configurations not possible to be obtained by either of them alone—viz., the radial and annular projections 25 and depressions, giving the appearance of the blending of the spoke and plate combined.

Fig. 1 is a perspective view, taken from the front of a car-wheel. A represents the face of hub; B, the radial convex corrugation, be-

ginning at the hub and blending into the annular corrugation at C; D, the reverse or radial concave corrugation, beginning at the hub and blending at D'; E, the convex annular corrugation, beginning at C and D', and extending into the rim or tread and running parallel with the same; F, the periphery or face of tread; G, the face of flange.

Fig. 2 is a perspective view of the back of the same wheel. 1 represents the hub; 2, the radial convex corrugation, beginning at the hub and blending into the annular corrugation at 3; 4, the reverse or concave radial corrugation, beginning at the hub and blending at 3'; 5, the concave annular corrugation, beginning at 3 and 3' and extending into the rim or tread, and running parallel with the same; 6, the back of flange.

Having thus described the nature of my design, what I claim, and desire to secure by Letters Patent, is—

The combination of the radial and annular corrugations, when used in the configuration of a web or plate of a car-wheel, substantially as herein described and set forth.

WILLIAM HAILES.
